UNITED STATES PATENT OFFICE

2,001,890

TYPE CYLINDER PRINTING DEVICE

Edward G. Rix, Chicago, Ill., assignor to The International Check Endorser Co., Chicago, Ill., a corporation of Illinois

Application June 3, 1932, Serial No. 615,164

6 Claims. (Cl. 101—350)

My invention relates to type cylinder printing devices.

One of the objects of my invention is to improve the operation of the clutch control and stop for the type cylinder.

A further object is to provide an improved drive for the ink roller.

Another object is to provide an improved ink distributing construction.

Further objects will be apparent from the description and claims.

In the drawings, in which my invention is illustrated:

Figure 1 is a plan view;

Fig. 2 is a section on the line 2—2 of Fig. 1;

Fig. 3 is a vertical axial section through the type cylinder and ink roller;

Fig. 4 is a detail of the clutch construction;

Fig. 5 is a further detail of the clutch construction;

Fig. 6 is a vertical part-sectional view of the drive for the type cylinder and ink roller;

Fig. 7 is a horizontal sectional view substantially on the line 7—7 of Fig. 6;

Fig. 8 is a vertical sectional view substantially on the line 8—8 of Fig. 9; and

Fig. 9 is a plan view of the ink well and ink-distributing construction.

The construction shown comprises a type cylinder 1, a rubber platen roller 2 yieldingly pressed toward the type cylinder, an ink well or reservoir 3, means for supplying ink from the well to the type cylinder as it rotates, a motor 4, and transmission 5 from the motor to the type cylinder and to the ink-supplying means.

The ink-supplying means comprises a rotatable rubber roller 6 for engaging the type on type cylinder 1 and a rotatable wooden spool 7 about half submerged in the ink in the ink-well and spring-pressed against the rubber roller.

In order to spread and distribute the ink evenly over the rubber roller 6, an intermittently rotatable scraper member 8 is provided, the roller portion 9 of which is spring-pressed against the rubber roller and the end of which is provided with a spur gear 10 which is intermittently advanced by means of a Geneva toothed gear 11 rotatable with the rubber roller 6. This intermittent advance of the scraper roller prevents any collection of lint or foreign material at the line of contact between the scraper and the rubber roller and the relative motion between the rubber roller and the scraper roller results in a scraping action which spreads the ink in a thin evenly distributed film over the rubber roller.

The scraper roller 9 is mounted in leaf spring bearings 12 which press it against the rubber roller 6. The tension in these leaf spring bearings may be adjusted by means of adjusting screws 13 threaded in the ink-well 3. The wooden spool 7 also is mounted in leaf spring bearings 14 which press it with a yielding pressure against the rubber roller. The rubber roller itself is driven from the motor by means of a flexible shaft 15 which permits up and down adjustment of the ink-well to secure just the right degree of contact between the rubber roller and the type on the type cylinder. This flexible shaft also enables the proper adjustment to be made when the ink roller is removed and reground.

I have found that it is desirable to form the wooden roller with a reduced central portion 16 in order to get just the right amount and distribution of ink on the rubber roller 6. The vertical adjustment of the ink-well 3 to which reference was made may be accomplished by means of a pair of screws 17, one on each end of the ink-well, each screw having its upper end swiveled in the framework 18 of the machine and having its lower end threaded into a laterally-extending lug 19 on the ink-well. By swiveling the screw in its mounting, the ink-well may be adjusted up or down to get just the right amount of contact between the rubber roller and the type cylinder. Strong compression springs 20 may be provided to hold the ink-well down as far as the head of the swiveled screw will allow it to go, thus preventing any jiggling up and down of the ink-well.

The transmission 5 from the motor 4 to the rubber roller 6 comprises, in addition to the flexible shaft 15 aforementioned, a worm 21 on the vertical shaft 22 of the motor and a worm gear 23 driven by this worm secured on the flexible shaft. This worm may be mounted in a suitable anti-friction bearing member 24 secured to the side frame 25 of the machine.

The transmission from the electric motor to the type cylinder comprises a second worm 26 mounted on the vertical motor shaft 22 and a worm gear 27 driven by this worm and mounted on the horizontal shaft 28 of the type cylinder 1.

Means are provided for connecting and disconnecting the type cylinder from its drive and stopping it in a definite position controlled by the insertion of the check or other paper to be printed.

The clutch and stop mechanism itself is substantially the same as that disclosed in the application of Lyman and Fischel, Serial No. 384,647, filed August 9, 1929. The check or paper control for this clutch and stop mechanism is designed

so that it will operate on very light pressure by the edge of the check or paper but will nevertheless give a strong, reliable movement to the clutch and stop controlling mechanism. This desirable result is accomplished by providing a power device controlled by the paper for operating the clutch and stop controlling mechanism.

In general, the clutch and stop mechanism comprises an oscillatable clutch member 29 rockably mounted on a collar 30 secured to the type cylinder shaft 28, and a rock arm 31 pivotally mounted at 32 and having a clutch throw-out and stop finger 33 for throwing out the clutch and stopping the type cylinder in just the right position. This throw-out and stop finger cooperates with a wedge formation 34 on the oscillatable clutch member 29 and with a shoulder formation on the type cylinder. A coil compression spring 36 tends to hold the control finger 33 down against a curved surface 37 on the stop plate which rotates with the type cylinder. Assuming that the finger 33 has been lifted to allow the clutch to engage and that the type cylinder is therefore being rotated, it will continue to rotate until the wedge formation on the clutch member engages the side of the control finger, whereupon the wedge formation will cause the clutch to be moved to disengaging position. The clutch disengagement will take place shortly before the shoulder on the shoulder plate engages the control finger but the momentum of the type cylinder will carry it on until the shoulder formation engages the control finger which stops it in a definite position.

The paper-controlled release mechanism for the control finger comprises a yoke-shaped rock member 38 having a pair of fingers 39 located in position to be engaged by the edge of the paper as it is drawn between the type cylinder and platen, a pair of electrical contacts 40 moved into engagement with each other by the cross bar 41 of the yoke member as it is rocked about its pivotal mounting at 42, an electromagnet 43 controlled by the contacts, and transmission 44 from the electromagnet to the rock member on which the control finger 33 is formed. This transmission may be simply a yoke 45 connected with the armature of the electromagnet and having a pivotal connection at 46 with the rock member.

In operation, when the slip of paper is passed between the type cylinder and platen, it depresses the fingers 39 of the yoke member 38, lifting the cross bar 41 of the yoke member and bringing the two contacts 40 together. This energizes the electromagnet 43, causing the control finger 33 to be lifted to release the control finger from the stop shoulder and allow the clutch spring 47 to throw the oscillatable clutch plate 29 into connecting position. The type cylinder 1 is then given one complete rotation, being released and stopped, as previously described.

Further modifications will be apparent to those skilled in the art and it is desired, therefore, that the invention be limited only by the prior art and the scope of the appended claims.

Having thus described my invention, what I claim and desire to secure by Letters Patent is:

1. A mechanism for supplying ink to a type cylinder rotatable about a horizontal axis comprising an ink reservoir, an ink supply roller rotat-

able about an axis parallel to the type cylinder and engaging said type cylinder, means for driving said roller at the same surface speed as said type cylinder, a rotatable scraper engaging said roller for spreading the ink on said roller, and means for rotating said scraper in the opposite direction to that of the roller at less average surface speed than the surface speed of the roller whereby the ink will be spread and foreign material such as lint and grit will be released from the 10 scraper as the scraper rotates.

2. A mechanism for supplying ink to a type cylinder rotatable about a horizontal axis comprising an ink reservoir, an ink supply roller rotatable about an axis parallel to the type cylinder and engaging said type cylinder, means for driving said roller at the same surface speed as said type cylinder, a scraper engaging said roller for spreading the ink thereon, and means for effecting movement of said scraper in a direction 15 to enable foreign material such as lint and grit to pass between the roller and scraper.

3. A mechanism for supplying ink to a type cylinder rotatable about a horizontal axis comprising an ink reservoir, an ink supply roller rotatable about an axis parallel to the type cylinder and engaging said type cylinder, means for driving said roller at the same surface speed as said type cylinder, and means whereby the roller may be adjusted toward and from the type cylinder, said driving means comprising a flexible 25 shaft.

4. A mechanism for supplying ink to a type cylinder rotatable about a horizontal axis comprising an ink reservoir, an ink supply roller rotatable about an axis parallel to the type cylinder and engaging said type cylinder, means whereby the roller may be adjusted toward and from the type cylinder, and means for driving said cylinder and roller comprising a worm shaft, 35 two worm gears driven from said worm shaft, and transmission from one worm gear to the cylinder and from the other worm gear to the roller.

5. A mechanism for supplying ink to a type cylinder rotatable about a horizontal axis comprising an ink reservoir, an ink supply roller rotatable about an axis parallel to the type cylinder and engaging said type cylinder, means whereby the roller may be adjusted toward and from the type cylinder, and means for driving said cylinder and roller comprising a worm shaft, two worm gears driven from said worm shaft, and transmission from one worm gear to the cylinder and from the other worm gear to the roller, said roller transmission comprising a flexible shaft. 45

6. A mechanism for supplying ink to a type cylinder rotatable about a horizontal axis comprising an ink reservoir, an ink supply roller rotatable about an axis parallel to the type cylinder and engaging said type cylinder, means for driving said roller at the same surface speed as said type cylinder, said roller being rotatably mounted on said reservoir, means whereby said reservoir may be adjusted toward and from the cylinder to vary the distance of the axis of the roller from the cylinder, and a flexible shaft for driving said roller.

EDWARD G. RIX.
